UNITED STATES PATENT OFFICE.

ALAN R. FERGUSSON AND CONSTANCE T. FERGUSSON, OF BUFFALO, NEW YORK.

SWITCH MECHANISM FOR TOY RAILWAYS.

Application filed April 17, 1923. Serial No. 632,610.

To all whom it may concern:

Be it known that we, ALAN R. FERGUSSON and CONSTANCE T. FERGUSSON, citizens of the United States, residing at Buffalo, in the county of Erie and State of New York, have invented certain new and useful Improvements in Switch Mechanism for Toy Railways, of which the following is a specification.

10 This invention relates to switch mechanism for toy or miniature railways, an object of the invention being to provide an improved toy or miniature switch structure which may be readily and economically manufactured, which may be manipulated or operated with great ease and facility without getting out of order, and which will be strongly and durably constructed so as to be practically indestructible and adapted 20 to withstand the hardest usage.

A further object of this invention is to provide a toy railway switch formed from wire rails mounted upon a composition or fiber board supporting platform and secured 25 in position for proper operation so as to form a firm, strong and stable structure having no wobbly or shaky joints or connections tending to impair operation or cause the switch to get out of order.

30 A further object of this invention is to provide an improved toy railway switch having a continuous platform support preferably formed from fiber or composition board constructed to simulate a railroad bed, 35 and having wire rail switch mechanism so mounted thereon and operated in an improved manner as to provide an efficient and advantageous toy device of great utility.

Other objects of this invention will appear in the following description and the appended claims thereof, reference being had to the accompanying drawings forming a part of this specification wherein like reference characters indicate corresponding parts 45 in the several views and wherein Fig. 1 is a plan view illustrating our invention; Fig. 2 is a longitudinal sectional view taken substantially on line 2-2 of Fig. 1; and Fig. 3 is a fragmentary perspective view illustrating the lever mechanism for operating the switching rails.

Before explaining in detail the present improvement and mode of operation thereof we desire to have it understood that the invention is not limited to the details of construction and arrangement of parts which

are illustrated in the accompanying drawings, since the invention is capable of other embodiments, and that the phraseology which we employ is for the purpose of description and not of limitation.

The present invention in general comprises a switch section having a continuous fiber or composition board support preferably simulating a railway bed, and mounted upon this board in fixed position are a pair of converging track sections formed from lengths of wire rail. Also mounted upon the platform support is a wire formed switching section including a pair of wire rails rigidly secured adjacent to one end thereof to the support and having the opposite ends free to be shifted into co-operation with the rails of either of the converging track sections. An improved self-locking lever mechanism is preferably provided for shifting the switching rails, and in order to provide an effective interlocking joint between the ends of the switching rails and either pair of rails of the converging sections, certain of the rails are notched at their ends so as to provide mating projections and recesses adapted to cooperate to form an effective joint.

Referring to the drawings it will be seen 85 that the rail parts forming the switch are mounted upon a platform support 9 cut to the desired shape and size and preferably formed from composition board or fiber. This platform support is readily adapted to 90 be printed or otherwise formed to simulate or resemble a railway bed, having imitation cross ties and rock ballast as clearly shown in Fig. 1. The fiber or composition board not only provides an advantageous medium 95 for securing the rails of the switch in position, but also forms a firm and stable support for the switch, and at the same time a readily portable, durable and cheap structure. The composition board is cut at one 100 end so as to accommodate a pair of converging track sections A and B. The track section A comprises an outer main line wire rail 10 secured to the supporting platform by means of rivets 11 which extend through the rail and support and rigidly hold the rail in position. The track section B comprises an outer curved wire rail 12 also riveted at 13 to the platform and thereby held in fixed position. The section A also 105 comprises a wire rail 14 extending in parallel relation to the rail 10 and riveted at

15 to the support, and a corresponding wire rail 16 of the section B and riveted at 17 to the support forms with the rail 14 a frog point 18. As illustrated the wire rails 14 and 16 are suitably tapered at their ends so as to unite to form a frog point and are preferably welded together. The section B also comprises an intermediate wire rail member 19 which is riveted at 20 to the supporting platform, and which extends in prolongation or alignment with the wire rail 16 but with the end thereof suitably spaced from the frog point 18. An intermediate wire rail 21 also terminates in spaced relation to the frog point 18 and is located in prolongation or alignment with the rail 14, this rail 21 also being secured or riveted at 22 to the composition board support.

20 The present toy railway switch is constructed for use in connection with an electrical toy railway system, and for this purpose the switch is provided with power rails for conducting current to the toy engine.

25 A power rail member 24 preferably formed of wire is mounted upon the platform intermediate the rails 10 and 14. A corresponding power rail member 23 is also mounted in position intermediate the rails 12 and 16.

30 Extending in prolongation of the power rail 24 is a power rail 25 having the end thereof preferably tapered and spaced from the intermediate rail 19. A third or power rail 28 is also located in position so as to be in

35 substantial prolongation or alignment with the third rail member 23. The several rails 23, 24, 25, and 28 are rigidly secured to the supporting platform so as to be held in relatively fixed position and these rail members

40 are preferably connected to the support by substantially similar means, this means preferably comprising rivets 26 projecting through the platform and wire rails. The several power rail members are preferably

45 spaced from the platform support so as to permit more effective engagement of the contact roller of the toy engine therewith, and in the present instance a washer 27 is interposed between the power rail and

50 the support and through which the rivet 26 extends.

The wire formed power rail 24 is preferably tapered at one end 24^a thereof so as to conform to the curvature of the rail 19 and 55 is preferably spot welded thereto to form a rigid joint. The power rail member 28 is also tapered at one end and preferably extends into a notch or recess 29 formed in the rail 25 and at this point the rails 28 and 25 60 are preferably welded together.

Mounted upon the fiber or composition board support is a wire formed switching section comprising a pair of spaced wire or cylindrical rails 30 and 32 located in parallel relation and adapted to be switched into

cooperation with either of the sections A and B. The wire rail 30 is secured at one end to the composition board support as by means of a rivet 31 extending through the rail and composition board, the opposite end of the rail being free from any connection with the support. The wire rail 32 is also secured at its corresponding end to the composition board support by means of a rivet 33, and the opposite end of this rail is also free from connection with the support. Extending transversely beneath the free ends of the switching rails 30 and 32 is a clamping link 34 secured as by means of rivets 35 to the rails. The rivets as shown in Fig. 2 60 preferably extend through the rails so as to firmly connect with the link 34 and the rails together. The platform support is provided with an extension 9^a and upon this extension is mounted a supporting plate 36 secured thereto as by means of screws 38 extending through holes 37 in the plate 36. Pivoted at 41 to the plate 36 is a horizontally swinging lever 39 having a projecting handle 40 at one end thereof for the purpose of manipulating the same. The opposite end of this lever is pivotally connected to the transverse link 34 by means of a link 42. This link 42 may be formed of wire extending through holes 43 and 44 in the ends of the link 34 95 and lever 39 respectively and bent or coiled so as to interlock the same together. At opposite sides of the swinging lever 39 the plate 36 is provided with bent up lugs or projections 45 and 46 forming stops for limiting the swinging movement of the lever.

In order to provide an efficient joint between the ends of the switching rails 30 and 32 and the several rails of the track sections A and B, the rail 32 at its extreme end is 105 notched or recessed at opposite sides to provide a projection 47. The wire rail 10 is also notched or recessed at 48. It will be seen from this construction that the notches in the ends of rails 10 and 32 will provide 110 mating projections and recesses forming a relatively perfect interlocking joint. Also it will be noted that the tapered end of the intermediate rail 19 will also fit into a notch 47 in the end of the rail 32 as shown in 115 Fig. 1, thus forming a smooth joint in this position of the switching rail 32. The juxtaposed ends of rails 12 and 30 are also notched on opposite sides so as to provide 120 mating projections 49 and 50 so that when these two rails cooperate or are located end to end the notches will permit the ends to mate and form a relatively perfect interlocking joint.

From the foregoing it will be understood 125 that the free spring ends of the switching rails 30 and 32 may be shifted horizontally under tension from their normal position in prolongation with the rails 10 and 21 of section A into prolongation with the rails 12 130

and 19 of section B. This is accomplished by grasping the handle 40 and swinging the lever 39 from the dotted line position shown in Fig. 1 to the full line position. In this operation the lever 39 will shift link 42 endwise, thus shifting transversely the link 34 and thereby switching the rails 30 and 32 into the full line position shown in Fig. 1. The lever 39 will be moved into self-locking position thereby automatically locking the rails 30 and 32 in their switching position and under tension. This is due to the fact that the pivot 41 will be shifted to the right of the line passing through the pivots 43 and 44. In order to switch the rails 30 and 32 back into their positions shown in dotted lines in Fig. 1, it is merely necessary to shift the lever 39 to the left sufficiently to cause the pivot 44 to pass beyond the line passing through the pivots 43 and 41, and thereupon the tension of rails 30 and 32 will operate to automatically return the rails to their normal position in alinement with the main rail section A.

For the purpose of releasably joining the opposite ends of the switch to the track sections of a toy railway, the several wire rails are provided with suitable dowels and dowel receiving ends. In the present instance the wire rails of sections A and B have the terminal ends thereof reduced or turned down to form projecting dowels 51. In joining these sections to a pair of adjacent sections of a toy railway it will be understood that the dowels 51 will be inserted in suitable tubular portions or dowel receiving ends of the adjacent rails. At the opposite end of the switch the wire rails 25, 30 and 32 are bored to receive tubular or dowel receiving portions 52.

It will be noted that the power rail 25 freely extends over the transverse link 34, and is suitably insulated therefrom by means of insulating strip 53 interposed between the rail and the link 34. It will be seen that the fiber or composition board support 9 not only provides a firm, portable support for the several rails but also forms an insulating medium so that the power rails may be rigidly secured in position thereon without necessitating the provision of any additional insulating means as has heretofore been the case where metal power rails have been mounted upon a metal foundation or metal rails.

It is to be understood that by describing in detail herein any particular form, structure, or arrangement, it is not intended to limit the invention beyond the terms of the several claims or the requirements of the prior art.

Having thus explained the nature of our invention and described a way of constructing and using the same, although without attempting to set forth all of the forms in

which is may be made, or all of the modes of its use, we claim:

1. In a toy railway switch the combination of a composition board support, two pairs of converging wire rails secured thereto, a pair of wire rails secured adjacent to the ends thereof to said support, and means including a swinging lever for shifting the opposite ends of said last rails into alinement with either of said first pairs of rails. 75
2. In a toy railway switch the combination of a composition board support, two pairs of converging wire rails secured thereto, a pair of wire rails secured adjacent to the ends thereof to said support, and means including a swinging lever pivoted to said support and link-connected to said last rails for shifting the opposite ends thereof into alinement with either of said first pairs of rails. 85
3. In a toy railway switch the combination of a platform support, a pair of wire formed switching rails secured at the ends thereof to the support, and a swinging lever for shifting the opposite ends of said rails under tension. 90
4. In a toy railway switch the combination of a platform support, a pair of wire formed switching rails secured at the ends thereof to the support, and a swinging lever adapted to be swung into self-locking position. 95
5. In a toy railway switch the combination of a platform support, a pair of wire formed switching rails secured at the ends thereof to the support, and a swinging lever for shifting the opposite ends of said rails under tension, said lever being pivoted for swinging movement into position to automatically lock said rails under tension. 100
6. In a toy railway switch the combination of a composition board support, two pairs of converging wire formed rails rigidly secured to said support, a pair of wire formed switching rails secured at the ends thereof to the support and having the opposite ends thereof free to shift into alinement with either of said first pairs of rails, and a swinging lever for shifting the same. 110
7. In a toy railway switch the combination of a composition board support, two pairs of converging wire formed rails rigidly secured to said support, a pair of wire formed switching rails secured at the ends thereof to the support and having the opposite ends thereof free to shift into alinement with either of said first pairs of rails, and a swinging self-locking lever for shifting the same. 115
8. In a toy railway switch the combination of two pairs of converging wire rails held in fixed relation, a pair of wire switching rails having notched ends, and means for shifting said notched ends into alinement with the same. 120
- 125
- 130

- ment with either of said first pairs of rails.
9. In a toy railway switch the combination of two pairs of converging wire rails held in fixed relation, a pair of wire switching rails having notched ends, and means for shifting said notched ends into alignment with either of said first pairs of rails, said means comprising a transverse link secured to said switching rails, a swinging lever, and a link connecting said lever and transverse link.
10. In a toy railway switch the combination of two pairs of converging wire rails, one of each having a notched end, a pair of wire switching rails having notched ends, and means for shifting said switching rails into position to bring into juxtaposition certain of said notched ends.
11. In a toy railway switch the combination of a composition board support, a pair of wire switching rails riveted adjacent to the ends thereof to said support and having the opposite ends free to swing in a horizontal path, and a swinging lever link-connected to said free ends for shifting the same in one direction under tension.
12. In a toy railway switch the combination of a composition board support, a pair of wire switching rails riveted adjacent to the ends thereof to said support and having the opposite ends free to swing in a horizontal path, and a swinging lever link-connected to said free ends for shifting the same in one direction under tension, said lever being pivoted for movement into self-locking position.
13. In a toy railway switch the combination of a composition board support, a pair of wire switching rails rigidly secured to said support adjacent to corresponding ends thereof and having the opposite ends free to swing in a horizontal path, a transverse link extending beneath said free ends and secured thereto, a swinging lever pivoted to said support, and a link pivotally connecting said lever and transverse link, said lever adapted to be shifted in one direction for shifting said switching rails under tension.
14. In a toy railway switch the combination of a composition board support, a pair of wire switching rails rigidly secured to said support adjacent to corresponding ends thereof and having the opposite ends free to swing in a horizontal path, a transverse link extending beneath said free ends and secured thereto, a swinging lever pivoted to said support, and a link pivotally connecting said lever and transverse link, said lever being shiftable in one direction to shift said switching rails and automatically lock the same under tension, and being automatically shifted by said rails in the opposite direction upon partially releasing the lever.
15. In a toy railway switch the combination of a continuous platform support, a pair of converging wire track sections rigidly secured to the support, and including each a wire power rail, and a wire switching section including a pair of switching rails rigidly secured at one end thereof to the support and having the opposite ends free to shift into cooperation with either of said track sections, said switching section having a wire power rail secured to said support in fixed position.
16. In a toy railway switch the combination of a composition board support constructed to simulate a railway bed, a pair of wire switching rails fixed to said support adjacent to one end of the rails and having the opposite ends thereof free to shift under tension, and a wire power rail secured to said support intermediate said rails and held in fixed position with relation thereto.
17. In a toy railway switch the combination of a composition board support constructed to simulate a railway bed, a pair of wire switching rails fixed to said support adjacent to one end of the rails and having the opposite ends thereof free to shift under tension, a wire power rail secured to said support intermediate said rails and held in fixed position with relation thereto, and a lever pivoted to said support and having connection with each of said free ends for shifting the same.
18. In a toy railway switch the combination of a composition board support constructed to simulate a railway bed, a pair of wire switching rails secured adjacent to one end thereof to said support and having the opposite ends forming free spring ends, one of said rails having a tubular dowel receiving end, and one having the free end thereof notched.
19. In a toy railway switch the combination of a pair of converging track sections including a wire rail having a fixed notched end, a switching section including a wire rail having a movable notched end, and means for shifting said movable notched end into position to mate with said fixed notched end thereby forming a joint.
20. In a toy railway switch the combination of a fiber or composition board support constructed to simulate a railway bed, a wire rail secured to said support and having a fixed notched end, a wire rail secured at one end to said support and having a movable notched end, and means for shifting the same whereby said notched ends will mate to form a joint.

Signed at Buffalo, N. Y., this 12th day of April, 1923.

ALAN R. FERGUSSON.
CONSTANCE T. FERGUSSON.
